(57) **CLAIM**

The ornamental design for a cooking tool, as shown and described.

DESCRIPTION

FIG. 1 is a top, right, front isometric view of the cooking tool.

FIG. 2 is a bottom, left, rear isometric view of the cooking tool.

FIG. 3 is a front elevation view of the cooking tool.

FIG. 4 is a rear elevation view of the cooking tool.

FIG. 5 is a top plan view of the cooking tool.

FIG. 6 is a bottom plan view of the cooking tool.

FIG. 7 is a right side elevation view of the cooking tool; and, FIG. 8 is a left side elevation view of the cooking tool.

The broken lines in FIGS. 1, 2, 5, and 6 illustrate portions of the cooking tool that are not part of the claimed design.
